CLEMMA R. RANEY, OF CHICAGO, ILLINOIS, ASSIGNOR TO INTERNATIONAL HARVESTER COMPANY OF NEW JERSEY, A CORPORATION OF NEW JERSEY.

GRAIN-SHOCKER.

1,222,798.

Specification of Letters Patent. Patented Apr. 17, 1917.

Application filed July 15, 1915. Serial No. 39,990.

To all whom it may concern:

Be it known that I, CLEMMA R. RANEY, a citizen of the United States, residing at Chicago, in the county of Cook and State of Illinois, have invented certain new and useful Improvements in Grain-Shockers, of which the following is a full, clear, and exact specification.

My invention relates to grain shockers.

10 It has for its object to deliver the sheaves ejected from a binder to a grain shucker in an improved manner whereby the capacity of the sheaf delivery mechanism is increased and the necessity for providing special 15 means controlling the time of operation of the sheaf discharging mechanism of the binder is minimized. A further object of my invention is to improve the sheaf delivery mechanism and controlling mechanism 20 of a grain shucker in such a manner as to produce a simple, rugged and efficient construction wherein the wear and tear upon the parts is also materially decreased. I attain these objects by an improved construction 25 and combination of sheaf delivery mechanism and controlling mechanism therefor wherein a plurality of sheaf delivery members operate to deliver the sheaves from the binder to the shock receptacle of the 30 shucker.

In the accompanying drawings I have shown, for purposes of illustration, one embodiment which my invention may assume in practice.

35 In these drawings—

Figure 1 is a plan view of a shucker equipped with my improvement;

Fig. 2 is a side elevation of the same;

Fig. 3 is a front elevation of the sheaf delivery mechanism carried on the shucker frame;

Fig. 4 is a detail view showing the sheaf delivery members and the clutch controlling mechanism;

45 Fig. 5 is a detail side elevation of the fork clutch and controlling mechanism therefor;

Fig. 6 is an end elevation of the mechanism shown in Fig. 5.

In these drawings I have illustrated my 50 invention as applied to a shucker of the general type described and claimed in my application, Serial No. 573,106, filed July 21, 1910, the shucker being connected at the rear end at the stubbleward side of a binder 1

and embodying substantially the elements 55 set forth therein, including the frame 2, the wheels 3, the rearwardly movable, normally prostrate shock receptacle 4, the binding mechanism 5, compressing mechanism 6, and dumping mechanism 7, all controlled by the 60 usual clutch mechanism 8 and operating in timed relation with the sheaf delivery mechanism, which is disposed in front of the receptacle 4 and acts to deliver a sheaf ejected from the binder deck 1 to the receptacle 4. 65

In my present improvement, as distinguished from the single sheaf delivery member shown in the above mentioned application, I provide a plurality of sheaf delivery members 9 and 10, each of which is adapted 70 to receive sheaves as they are ejected from the binder deck 1 by the discharge mechanism 11 of the binder and the supplemental sheaf ejecting mechanism 12. As in the construction set forth in another copending 75 application, Serial No. 801,527, filed November 17, 1913, these sheaf delivery members are each controlled by a clutch 13 and a clutch controlling member 14 located upon the binder deck in the path of a sheaf delivered from the binder, this controlling member being operatively connected to a plurality of sheaf stopping members 15 mounted upon a rocking member 16, which is in turn connected to the clutch 13. The 80 rod 14 shown in Fig. 3 passes through a slotted lever 140 above the pivot and is connected by means of link 141 to a depending arm 142 fixed on the rocking member 16, and by means of these pivot connections the 85 rocking member 16 is controlled by the clutch controlling member 14, as well as by means of the sheaf stopping members 15, which are mounted directly upon said rocking member. Each of these sheaf delivery 90 members 9 and 10 also co-operates with size control mechanism of the type described in my copending application, Serial No. 743,740, filed January 23, 1913, in which the mechanism controlling the binding and 95 dumping of the shock is actuated by the sheaf delivery member when the sheaves have reached a predetermined height in the receptacle 4, the clutch mechanism 8 then being tripped into operation. This mechanism includes a trip member 17 movable 100 with each fork and normally running alternately on the upper and lower surfaces of an

arcuate cam 28 until, when the shock in the receptacle 4 has reached a certain height, this trip member 17 is reversed in its movement and in going back over the upper surface of the cam 28, throws a trip 19, which is connected through a spring and link connection 20 to the clutch 8.

These sheaf delivery members 9 and 10 are movable alternately into position beneath the discharging mechanism 11 on the binder and are successively movable upward and rearward to deliver the sheaves to the shock receptacle 4. They are preferably driven from a single power shaft 21 rotated by any suitable means; as, for instance, in the manner described in any of my applications mentioned above. This shaft 21 is provided with a plurality of oppositely disposed cranks 22 and 23, and these cranks 22 and 23 are preferably connected through resilient pitmen 24 and 25 and rock arms 25' of the construction described in application Serial No. 573,106, filed July 21, 1910, to a fork shaft 26, which is fixed to a supplementary or front frame 27 at the front of the shocker frame 2. Movable with each of these pitmen, and rotated upon the fork shaft 26 through driving connections of the type described in my copending application Serial No. 542,535, filed January 17, 1913, are the sheaf delivery members 9 and 10. Movable with each of these delivery members is also a clutch actuating member 17. As shown, these clutch actuating members move in opposite directions across the opposite sides of a double winged cam 28 carried on a bracket 29 on the shaft 26, the members 17 preferably being in the form of rollers and passing successively on the upper and lower surfaces of the cams 28 as a shock is built up in the receptacle 4 after the manner described above in my copending application, Serial No. 743,740, filed January 23, 1913. In this construction, however, the tripping member 19 is engaged by the roller 17 on each delivery member and is itself pivoted at a single point 30 on the stud or lug extending above the cam surfaces 28 on the bracket 29 so that a roller 17 moving back over either of the upper cam surfaces can actuate it.

As the forks 9 and 10 move rearward in building up a shock, it is also to be noted that they are so guided in their movement that they build in the sheaf receptacle 4 a shock in which the heads of the sheaves converge or overlap and the butts diverge. This I here accomplish by each time deflecting the same fork to the same side of the receptacle, as distinguished from my previous constructions, wherein a single fork is used and deflected to different sides of the receptacle. In bringing about such a fork movement, a plurality of stationary guides 31 and 32 are provided, of substantially the

same conformation, but oppositely curved at their front ends. As shown, the guide 31 has a curved portion 33 extending upward and laterally in such a manner that as the fork adjacent the binder is raised, through 73 the engagement of its guiding rollers 34, it is deflected laterally before it reaches a vertical position in such a manner that it clears the deck and discharging mechanism of the binder. After a predetermined movement 75 laterally, due to the conformation of both the guides 31 and 32, the forks are again deflected so that they then move approximately straight rearwardly. Obviously, by such a construction, with the sheaf delivery members working alternately, as they must by reason of their driving connection 21 and 22, these members will move upward and laterally in such a manner as effectually to clear the bundle discharging mechanism of 85 the binder, at the same time that they avoid conflict one with the other.

It will also be noted that as the forks move rearward to deliver sheaves to the shock receptacle, they are each cushioned and given 90 a return kick or impulse by a plurality of springs 35, 36, which in general perform the function described in my application Serial No. 742,535, filed January 17, 1913. Of these springs, the former are connected 95 between the front of the frame 2 and a fixed part movable with the fork; as, for instance, to a part movable with the controlling member 17. The springs 36, shown herein, however, are coiled about the rear 100 ends of the guides 31 and 32 and are preferably provided with suitable collars or compression members 37 engageable with the rollers 34 on the sheaf delivery members 9 and 10 when the latter approach their sheaf 105 delivering positions. In this construction it is to be noted that while the functions obtained by the double spring mechanism are substantially those described in my co-pending application mentioned above, a far 110 greater simplicity of the spring mechanism and a materially reduced cost of manufacture is made possible.

Coöperating with these sheaf delivery members 9 and 10, and acting to time the movement of the same, is the clutch controlling mechanism 14, 15, 16, etc., which controls the clutch 13 on the shaft 21. In the present construction the member 16 is connected to the tripping member 14 and 120 rocked in substantially the same manner as in my copending application, Serial No. 801,527, filed November 17, 1913, mentioned above, and a single spring 38 acts to hold a clutch controlling member 39 in the path 125 of the stop dog 40 of the clutch. It will be noted, however, that upon the member 16 a second controlling member 41 is provided which is so disposed with respect to the member 39 that, with that member, it acts 130

to interrupt the movement of the clutch dog 40 after each half revolution of the latter, the members 39 and 41 alternating in their function of interrupting the action of the clutch. Tracing this action through to the sheaf delivery members 9 and 10, it will be seen that by this mechanism these sheaf delivery members are successively driven from sheaf receiving to sheaf discharging position and back again, the clutch mechanism 13 being thrown out temporarily when one of the same has returned to its sheaf receiving position and remaining out until the next sheaf discharged from the binder deck 15 causes it to be again connected.

Coöperating with this mechanism is also the mechanism for rendering the sheaf delivery mechanism inoperative, which I have also specifically improved, the same preferably taking the form of a plain flat strap or rod 42 resiliently connected at 43 at a point above the knotter and needle operating links 51. As shown, this rod 42 is actuated in the manner described in my copending application, Serial No. 742,535, filed January 17, 1913, when the binding mechanism is operated through the links 51. This operation is, of course, not changed. It will, however, be noted that the rod 42 does not 20 in this construction engage with the stop dog 40 in any way, the lower end simply moving through a guide or slotted way 44 carried on the frame to engage the side of the front controlling member 39, as shown in 25 Figs. 5 and 6, and thereby cause the same to be held in and the sheaf delivery mechanism to be rendered inoperative.

In the operation of my improved construction, the sheaf delivery members 9 and 10 are successively actuated as sheaves are ejected from the binding mechanism of the binder by the discharge arms 11 through the controlling or tripping member 14 on the binder deck, and if necessary by the action 40 of the stop members 15, all in a well-known manner. For instance, let us assume that the members 10 are in the position shown in Figs. 1 and 2. A bundle trips off the clutch 13. As the sheaf delivery member 45 10 moves backward, the member 9 will obviously move forward, or to sheaf receiving position, the two members then moving in opposite directions along their curved guides 31 and 32 so that when the member 50 10 is delivering its sheaf to the shock receptacle 4, the sheaf delivery member 9 will be receiving another sheaf from the binding mechanism on the binder. So far as the controlling mechanism is concerned, it is also 55 obvious that, by means of the two controlling members 39 and 41, the trip dog or clutch dog 40 of the clutch 13 will be interrupted in its movement at each half revolution, each sheaf delivery member being set 60 in operation by the sheaf which is to be car-

ried thereby acting upon the tripping member 14 or the stopping members 15. It will also be noted that as each sheaf delivery member moves rearward, it will act to compress its spring 36 in such a manner as to 65 store up the requisite energy therein to give the delivery member the desired backward kick or separating movement, tending to withdraw its tines from the delivered bundle. Obviously, as each sheaf goes backward, its clutch controlling member 17 will 70 pass over its cam surface 28 and as it returns to sheaf receiving position will also pass under this cam surface. This will continue until the sheaves in the shock receptacle 75 have reached a certain height, when the fork will be unable to move down far enough in the receptacle to let the roller 17 pass under the cam. When this occurs, the roller 17, through its driving connection, will be carried 80 back over the top of the cam and will trip the tripping member 19 controlling the clutch 8, thus throwing the binding, compressing and dumping mechanism of the shocker into operation. While this mechanism is operating and the shock is being 85 compressed, bound and dumped, the clutch controlling member 42 will move down in the guide 44 in such a manner as to hold the clutch 13 out of operation, both of the 90 controlling members 39 and 41 being held in clutch engaging position by the member 42 (Fig. 5) and the clutch remaining out of 95 operation until the compressing, binding and dumping operation is completed.

It is to be noted that in this construction, wherein a plurality of sheaf delivery members is used, the time which must elapse between the delivery of each sheaf in a single-fork shocker is reduced by one-half. 100 This results in a material increase in capacity of the shocker, enabling it to operate under the most extreme conditions. It further acts to minimize the necessity for separate control mechanism for the discharging 105 mechanism on the binder, the time interval during which a sheaf delivery member is not in sheaf receiving position being so reduced that the necessity for locking the mechanism to prevent a sheaf from being ejected when 110 the sheaf delivery member is out of position is proportionately reduced. It will also be noted that the wear and tear upon the parts is but half that where a single sheaf delivery member is used and that a strong, simple 115 and efficient mechanism is obtained. These 120 and other advantages of my improvement will be clearly apparent, however, to one skilled in this art.

While I have in this application specifically described one embodiment which my invention may assume in practice, it will be understood that this form is chosen for purposes of illustration, and that the invention itself is in nowise limited thereto or to the 125 130

specific details set forth, the same being capable of use in other forms and of modification without departing from its spirit.

What I claim as new is:

- 5 1. In combination, a binder, sheaf discharging mechanism thereon, a plurality of oscillatory sheaf delivery members receiving sheaves therefrom, and means for moving the same alternately in opposite directions.
- 10 2. In combination, sheaf discharging mechanism, a plurality of sheaf delivery members receiving sheaves therefrom, and means for moving the same in opposite directions through diverging paths.
- 15 3. In combination, a plurality of normally prostrate upwardly movable oscillatory sheaf delivery members, and means for moving the same successively to and from the same initial position.
- 20 4. In combination, a plurality of oscillating sheaf delivery members, and means for moving the same successively through diverging paths from a common starting point which they successively occupy.
- 25 5. In combination, sheaf discharging mechanism, a shock receptacle, a plurality of oscillatory sheaf delivery members, and operating means therefor moving one of the same into sheaf receiving position adjacent said discharging mechanism while another delivers a sheaf to said receptacle.
- 30 6. In a grain shocker, sheaf discharging mechanism, an oscillatory sheaf delivery member receiving sheaves therefrom, means coöperating therewith including a second sheaf delivery member movable into position adjacent said sheaf discharging mechanism as said first mentioned member is moved away therefrom.
- 35 7. In combination, sheaf binding and discharging mechanism, a normally prostrate shock receptacle, and means including a plurality of successively acting normally prostrate sheaf delivery members receiving sheaves from said binding and discharging mechanism and delivering the same prostrate in said receptacle.
- 40 8. In combination, a binder, sheaf discharging mechanism thereon, a plurality of upwardly swinging sheaf delivery members pivoted on a common axis, and means for moving the same in opposite directions through diverging paths and returning the same successively through the same path to a single starting point.
- 45 9. In a shocker, a shock receptacle, a frame, a plurality of movable sheaf delivery members pivoted on said frame for delivering sheaves to said receptacle, operating mechanism therefor, and means for moving said sheaf delivery members through diverging paths as they swing about their pivots.
- 50 10. In a shocker, a shock receptacle, a frame, a plurality of upwardly and rear-

wardly movable sheaf delivery members pivoted on said frame for delivering sheaves to said receptacle, operating mechanism therefor, and means for moving said sheaf delivery members through diverging paths as they swing about their pivots.

11. In a grain shocker, shock binding and dumping mechanism, mechanism including a plurality of swinging sheaf delivery members delivering sheaves thereto, and means for controlling said binding and dumping mechanism set in operation by one of said delivery members.

12. In a grain shocker, shock setting mechanism, mechanism including a plurality of swinging sheaf delivery members delivering sheaves thereto, and means controlling said shock setting mechanism set in operation by any one of said delivery members.

13. In a grain shocker, shock setting mechanism, mechanism including a plurality of swinging sheaf delivery members delivering sheaves thereto, and means controlling said setting mechanism set in operation by one of said delivery members when the shock has reached a predetermined size.

14. In a grain shocker, shock setting mechanism, mechanism including a plurality of swinging sheaf delivery members delivering sheaves thereto, and means controlling said setting mechanism set in operation by any one of said delivery members when the shock has reached a predetermined size.

15. In a grain shocker, a frame, a sheaf delivery member pivoted thereon, a guiding bail therefor carried on said frame, and a coiled spring encircling said bail and disposed in the path of movement of said delivery member.

16. In a grain shocker, a frame, a sheaf delivery member pivoted thereon, a guiding bail therefor carried on said frame, a sliding connection between said member and bail, and a coiled spring encircling said bail and engageable by said connection.

17. In a grain shocker, a frame, a sheaf delivery member pivoted thereon, an arcuate guiding bail therefor, and a coiled spring encircling one end of said bail disposed at one end of the path of movement of said delivery member.

18. In a grain shocker, a frame, a crank shaft thereon having a plurality of cranks thereon, a shaft disposed adjacent said crank shaft, pitmen connecting the cranks on said crank shaft to said second shaft, and a plurality of sheaf delivery members operatively connected to said second shaft and pitmen.

19. In a grain shocker, a frame, a plurality of sheaf delivery members thereon, operating mechanism therefor including a clutch, and means controlled by the sheaves delivered to said delivery members for disconnecting said clutch at a plurality of points.

20. In a grain shocker, a frame, a plurality

of sheaf delivery members thereon, operating means therefor including a clutch, clutch releasing mechanism including a plurality of clutch controlling members in turn controlled by the sheaves delivered to said delivery members.

21. In a grain shocker, a frame, a plurality of sheaf delivery members thereon, operating mechanism therefor including a clutch having a rotary clutch dog, and a clutch controlling member having a plurality of dog engaging members engageable with the dog at different points in the rotation of the latter.

22. In a grain shocker, a frame, a plurality of swinging sheaf delivery members thereon, a cam member disposed between said members having oppositely extending ledges thereon, a clutch controlling member pivoted on said cam member and projecting to a point adjacent each of its surfaces, clutch mechanism operatively connected to said member, and means on each of said delivery members engageable with said cam surfaces and with said clutch controlling member.

23. In a grain shocker, a frame, a plurality of sheaf delivery members thereon, operating mechanism therefor including a clutch having a rotating dog, a plurality of clutch controlling members engageable with said dog at different points in its travel and themselves controlled by the sheaves delivered to said delivery members, automatic binding mechanism for binding the sheaves delivered by said delivery members, and means controlled by said binding mechanism for rendering said clutch controlling members inoperative.

24. In a grain shocker, a frame, a plurality of sheaf delivery members thereon, operating mechanism therefor including a clutch having a rotating dog, a plurality of clutch controlling members engageable with said dog at different points in its travel and themselves controlled by the sheaves delivered to said delivery members, automatic binding mechanism for binding the sheaves delivered by said delivery members, and a member movable upon actuation of said binding mechanism to throw one of said clutch controlling members out of the path of said dog.

25. In a grain shocker, a frame, a plurality of sheaf delivery members thereon, operat-

ing mechanism therefor including a clutch having a rotating dog, tripping mechanism 55 for said clutch including a plurality of clutch controlling members engageable with said dog after each half revolution of the same, automatic binding mechanism for binding the shock built by said delivery 60 members, a guide carried on said frame adjacent said controlling members, and a member operable by said binding mechanism and movable in said guide engageable with one of said clutch controlling members. 65

26. In a shocker, a plurality of sheaf delivery members, actuating means therefor including a single controlling clutch, shock binding mechanism, and means under the control of said shock binding mechanism for 70 disconnecting the sheaf delivery members from their actuating means by throwing out said clutch during the shock binding operation.

27. In a shocker, a plurality of success- 75 sively acting sheaf delivery members, actuating means therefor, and means set in operation when the shock has reached a predetermined size for disconnecting the sheaf delivery members from their actuating 80 means.

28. In a shocker, a plurality of success- 85 sively acting sheaf delivery members, a common actuating shaft therefor, a single clutch controlling said shaft, a plurality of pawls controlling said clutch, and means for throwing said pawls simultaneously into operative relation with said clutch.

29. In a shocker, a plurality of success- 90 sively acting sheaf delivery members, a common actuating shaft therefor, a single clutch controlling said shaft, a plurality of pawls controlling said clutch, and means set in operation when the shock has reached a predetermined size for throwing said pawls 95 simultaneously into operative relation with said clutch.

30. In a shocker, a plurality of sheaf delivery members, actuating means therefor including a single controlling clutch, and 100 means for rendering said clutch ineffective when the sheaf has reached a predetermined size.

In testimony whereof I affix my signature.

CLEMMA R. RANEY.
